[57] CLAIM

The ornamental design for a combined heating base, hair curlers, and cover therefor, as shown and described.

DESCRIPTION

FIG. 1 is a top plan view of a combined heating base, hair curlers and cover therefor showing my new design; FIG. 2 is a front elevational view thereof; FIG. 3 is a rear elevational view thereof; FIG. 4 is a left side elevational view thereof; FIG. 5 is a right end elevational view thereof; FIG. 6 is a bottom plan view thereof; FIG. 7 is a top plan view of a second modified embodiment; and, FIG. 8 is a front elevational view thereof.

The undisclosed portions of the embodiment represented in FIGS. 7 and 8 are identical to those of the first disclosed embodiment, except for the appearance of equal sized curlers.

FIG. 3

FIG. 5
